(57) **CLAIM**

The ornamental design for a nozzle for syringe, as shown and described.

DESCRIPTION

FIG. 1 is a perspective view of a nozzle for a syringe showing the new design for a nozzle for syringe, where the outer surfaces are transparent;

FIG. 2 is a right side view thereof, the left side view being a mirror image thereof;

FIG. 3 is a top view thereof;

FIG. 4 is a bottom view thereof;

FIG. 5 is a front view thereof; and,

FIG. 6 is a rear view thereof.

The nozzle for syringe is shown with a symbolic break in its length. The appearance of any portion of the article between the break lines forms no part of the claimed design.

The portions of the nozzle for syringe in FIGS. 1-6 shown in broken lines are included to show features that form no part of the claimed design.
